UNITED STATES PATENT OFFICE.

MARTIN CHRISTENSEN, OF RACINE, WISCONSIN, ASSIGNOR TO CHRISTENSEN MACHINE COMPANY, OF RACINE, WISCONSIN, A CORPORATION OF WISCONSIN.

DELIVERY MECHANISM FOR SIGNATURE-STITCHING MACHINES.

1,423,647.

Specification of Letters Patent. Patented July 25, 1922.

Application filed June 3, 1920. Serial No. 386,236.

To all whom it may concern:

Be it known that I, MARTIN CHRISTENSEN, a citizen of the United States, and resident of Racine, in the county of Racine and State 5 of Wisconsin, have invented new and useful Improvements in Delivery Mechanism for Signature-Stitching Machines, of which the following is a description, reference being had to the accompanying drawings, which 10 are a part of this specification.

The present invention relates to certain new and useful improvements in signature stitching machines and has for one of its objects to provide improved delivery means 15 so constructed and positioned as to save floor space and permit better supervision of the work of the machine.

Another object of this invention is to provide means for positively feeding the signatures from the discharge mechanism of the 20 machine to the delivery belt and for preventing the folding of the signatures during such feeding operation.

A further object of my invention is to 25 provide means for delivering signatures from the front side of a signature stitching machine which will be simple in construction, efficient and positive in operation, and capable of production at a comparatively 30 small expense, all things considered.

With the above and other objects in view which will appear as the description proceeds, my invention resides in the novel construction, combination and arrangement of 35 parts substantially as hereinafter described and more particularly defined by the appended claims, it being understood that such changes in the precise embodiment of my invention may be made as come within the 40 scope of the claims.

In the accompanying drawings I have 45 illustrated one complete example of the physical embodiment of my invention constructed according to the best mode I have so far devised for the practical application of the principles thereof, and in which:

Figure 1 is a side view of my improved delivery mechanism, said view being taken on the plane indicated by the line 1—1 of 50 Figure 4, a portion of the delivery end of a signature stitching machine being shown in transverse section.

Figure 2 is a view part in section and

part in elevation taken on the plane indicated by the line 2—2 of Figure 1.

Figure 3 is a fragmentary detail view of the outer end of two of the series of delivery belts.

Figure 4 is a view looking at the front of my improved delivery mechanism, said view 60 being taken on the plane indicated by line 4—4 of Figure 1.

Figure 5 is a view part in section and part in rear elevation of the receiving end 65 of my improved delivery mechanism, said view being taken on the plane indicated by the line 5—5 of Figure 1, and

Figure 6 is a sectional view taken through the receiving end of my delivery mechanism on the line 6—6 of Figure 5.

In stitching machines, after the groups of signatures are stitched by the stitchers, they are fed to the discharge means of the machine by the stitcher feed and are then discharged from the machine, and the present 75 invention relates to delivery mechanism for receiving the discharged signatures at the front side of the machine whereby the operator of the machine may supervise the finished work and whereby considerable floor 80 space is saved by various arrangements of parts.

The finished signatures 10 are fed along the signature saddle 11 to the discharge end D of the stitching machine by means of the 85 feeding mechanism (not shown), and are then ejected from the machine over rollers 12 between endless belts 13 carried by pulleys 14 journaled in the bearing brackets 15.

My delivery mechanism consists of side 90 bracket members 16 having their lower ends formed with securing flanges 17 which are secured to the machine frame 18 by suitable fastenings 19 and having their upper outer end provided with upstanding ears or lugs 95 20 to which are pivotally secured the ends of a transverse bar 21. The transverse bar 21 has secured thereto in spaced relation as at 22 the inner ends of a plurality of forwardly extending bars 23 each having a 100 bearing member 24 secured to its outer end and being connected together by a transverse bar 25 secured to each bar 23 adjacent their outer ends.

The outer end of the frame formed by the 105 members 21, 23 and 25 is supported at the

proper height from the floor by means of standards 26 having their upper ends secured to the transverse bar 25.

The bearing portion 27 is formed on the 5 upper end of each bracket member 16 rearwardly of the projection 20 and has journalled therein the adjacent end of a shaft 28 upon which a plurality of rollers or pulleys 29 are mounted in line with each bar 23. A 10 roller or pulley 30 is journalled in the outer end of each bearing bracket 24, and the pulleys 29 and 30 in line with the same bar 23 are connected by means of an endless belt 31. The plurality of endless delivery belts 15 thus provided are arranged in spaced relation form the means for delivering the discharged signatures from the stitching machine.

The conveying belts 31 are adapted to be 20 simultaneously intermittently advanced and this movement is imparted thereto by means of a drive connection between the shaft 37 and the driven shaft 32 in connection with the drive (not shown) of the stitching machine. The shaft 32 is journalled in a bearing 33 formed on the innermost bearing bracket 16 and has mounted thereon an eccentric cam 34 on which tracks a roller member 35 journalled in the free end of an arm 36 having its upper end fixed to a shaft 37 having its end journalled in the bracket members 16. The inner ends of the shafts 28 and 37 are projected slightly beyond the adjacent bearing bracket 16 and have a 25 ratchet wheel 39 and a crank arm 40 secured thereto respectively. The crank arm 40 has pivotally secured thereto one end of a pawl 41 and its free end 42 engaging the periphery of the ratchet wheel 39 so that a movement to the left, with reference to Figure 1 of the crank arm 40 will impart a counter-clockwise partial rotation to the ratchet wheel 39 and consequently to the conveyor belts 31.

45 As the receiving end of the conveyor belts are positioned beneath the discharge means of the stitching machine, I provide means for receiving the signatures 10, as they are discharged, and placing the same upon the belt 31 in semi-packed or stacked relation, and this means consists of a plurality of feed fingers 43 having their inner ends secured to collars 44 mounted on the shaft 37 in spaced relation, one being disposed 50 centrally of each adjacent pair of delivery belts. The collars 44 are so positioned on the shaft 37 that when the eccentric cam 34 is positioned as in Figure 1, the upper free ends of the feed fingers will be positioned 55 adjacent the discharge rollers 12 of the stitching machine so that the signatures 10 will slide downwardly on the fingers to the 60 position depicted in Figure 1.

In order to insure the sliding against the 65 feed fingers of the signatures, a plurality of

guide fingers 45 are depended from the bearing bracket 15 and arranged in spaced relation so that the feed fingers 43 in their oscillation will pass therebetween. The roller 35 is at all times yieldingly urged to engage the periphery of the eccentric cam 34 by means of a contractile spring 46 having one end secured to the machine frame and its other end secured to a depending arm 47 secured as at 48 to the shaft 37.

As the signatures being handled are often-times formed of very flimsy material and their lower edges slide away from the feed fingers, I provide means for preventing this sliding away of the lower edges of the signatures, which means are withdrawn from the path of the signatures upon actuation of the feed fingers by the cam 34. This means includes a plurality of vertical stop fingers 49 having their lower ends secured to a bar 50 having its outer end journalled in the outer ends 51 of levers 52 having their inner ends fixed to a shaft 53 journalled in bearings 54 secured to the machine frame. The upper ends of the stop fingers 49 are guided through apertures in a brace bar 55 extending across the space between the bracket members 16 just beneath the top half of the conveying belts and secured to the bracket members 16 as at 56. As best shown in Figures 4 and 5, a stop finger 49 is positioned at each side of each feed finger 43, and I provide means for depressing the stop fingers 49 immediately upon the movement of the feed fingers 43 from their full line position in Figure 1 to the dotted line position.

The feed fingers 49 are actuated by means of an eccentric cam 57 fixed to the shaft 32 and having tracking thereon a roller 58 journalled in one end of a lever 59 secured to the shaft 53. The roller 58 is resiliently urged at all times to engage with the periphery of the eccentric cam 57 by means of two extensile springs 60 coiled about two of the fingers 49 and having their ends bearing against the bar 50 and the underside of the bar 55.

As best shown in Figure 1, with the eccentric cams 34 and 57 in their full line positions depicted in Figure 1, the stops 49 will be at their full limit of movement, the conveyor belts 31 stationary and the feed fingers 43 positioned with their upper ends adjacent the discharge rollers 12 to receive the signature about to be discharged from the stitching machine, the shaft 32 being so timed with the discharge mechanism of the stitching machine to insure this relative position of the various parts. Immediately upon the discharge of the signatures from the stitching machine, the cam 34, which is continually rotating, permits the roller 35 carried by the arm 37 to move to the left, with reference to Figure 1 under actuation of the

spring 46 and thus advance the belts 31 and also move the feed fingers 43 to the dotted line position.

The cam 57 is so positioned with respect 5 to the eccentric cam 34 that immediately upon movement of the feed fingers from their full line position depicted in Figure 1, the roller 58 will be permitted to move to the left with reference to Figure 1 under 10 action of its springs 60. The tops of the fingers 49 will then be positioned flush with the top of the cross bar 55.

From the foregoing description taken in connection with the accompanying drawings, 15 it will be at once apparent to those skilled in the art to which an invention of this character appertains, that by positioning the delivering mechanism on the front side of the machine, one person can operate 20 the machine and at the same time supervise the completed signatures; that a large amount of floor space is saved by the machine; and that the efficiency of the entire machine is increased.

25 What I claim as my invention is:

1. In apparatus of the class described, the combination of a frame including a horizontally extending portion having its inner end positioned adjacent the discharge end of 30 a stitching machine or the like, rollers journaled in the inner and outer ends of said horizontal frame portion, a belt on said rollers, a shaft journaled in said frame, a feed finger mounted on said shaft, a bell 35 crank fixed on said shaft, a drive shaft, a cam on said drive shaft, means to maintain one arm of said bell crank in operative engagement with said cam, a ratchet associated with one of said rollers, and a pawl 40 carried by the other arm of said bell crank and adapted to engage said ratchet, whereby said belt is intermittently advanced and said feed finger is simultaneously oscillated, for the purpose specified.

45 2. In apparatus of the class described, the combination of a frame including a horizontally extending portion having its inner end positioned adjacent the discharge end of a stitching machine, or the like, a shaft 50 journaled in the inner end and a plurality of spaced rollers journaled in the outer end of said horizontal frame portion, a plurality of rollers on said shaft in alignment with said first mentioned rollers, belts on 55 said respective sets of rollers, a second shaft journaled in said frame, a plurality of feed fingers mounted on second shaft and projecting upwardly between said belts, respectively, a bell crank fixed on said second 60 shaft, a drive shaft, a cam on said drive shaft, means to maintain one arm of said bell crank in operative engagement with said cam, a ratchet associated with said first mentioned shaft, and a pawl carried by the 65 other arm of said bell crank and adapted

to engage said ratchet, whereby said belts are intermittently advanced and said feed fingers are simultaneously oscillated, for the purpose specified.

3. In apparatus of the class described, 70 the combination of a frame including a horizontally extending portion having its inner end positioned adjacent the discharge end of a stitching machine, or the like, rollers journaled in the inner and outer ends of 75 said horizontal frame portion, a belt on said rollers, a shaft journaled in said frame, a feed finger mounted on said shaft, a bell crank fixed on said shaft, a drive shaft, a cam on said drive shaft, a ratchet associated 80 with one of said rollers, a pawl carried by the other arm of said bell crank and adapted to engage said ratchet, a rock shaft journaled in said frame, a bell crank mounted on said rock shaft, a stop finger 85 carried by one arm of said last mentioned bell crank, a second cam on said drive shaft adapted to bear against the other arm of said last mentioned bell crank, and means to maintain said bell cranks in operative 90 engagement with said cams, respectively, whereby said stop finger is moved into inoperative position, said belt intermittently advanced and said feed finger oscillated, for the purpose specified. 95

4. In apparatus of the class described, the combination of a frame including a horizontally extending portion having its inner end positioned adjacent the discharge end of a stitching machine or the like, a shaft 100 journaled in the inner end and a plurality of spaced rollers journaled in the outer end of said horizontal frame portion, a plurality of rollers on said shaft in alignment with said first mentioned rollers, belts on 105 said respective sets of rollers, a second shaft journaled in said frame, a plurality of feed fingers mounted on second shaft and projecting upwardly between said belts, respectively, a bell crank fixed on said second 110 shaft, a drive shaft, a cam on said drive shaft, a ratchet associated with said first mentioned shaft, a pawl carried by the other arm of said bell crank and adapted to engage said ratchet, a rock shaft journaled in 115 said frame, a bell crank mounted on said rock shaft, a transversely extending bar connected to one arm of said last mentioned bell crank, a plurality of stop fingers carried by said bar and adapted to project 120 upwardly between said belts, respectively, a second cam on said drive shaft and adapted to engage the other arm of said last mentioned bell crank, and means to maintain said bell cranks in operative engagement 125 with said cams, respectively, for the purpose specified.

In testimony whereof, I affix my signature.

MARTIN CHRISTENSEN.
